UNITED STATES PATENT OFFICE.

JAMES A. ANDERSON, OF CHICKASHA, OKLAHOMA.

BLOWTORCH.

1,383,276.

Specification of Letters Patent.

Patented July 5, 1921.

Application filed October 29, 1920. Serial No. 420,550.

To all whom it may concern:

Be it known that I, JAMES A. ANDERSON, a citizen of the United States of America, residing at Chickasha, in the county of 5 Grady and State of Oklahoma, have invented certain new and useful Improvements in Blowtorches, of which the following is a specification.

This invention relates to a blow torch, utilizing 10 gasolene or the like as a fuel, and constructed to avoid the necessity of heating the escaping vapor to convert it into a gas for ignition.

The invention is particularly directed to 15 providing in connection with the torch proper and as a part thereof, an igniting means, adjustable with relation to the torch to direct the flames from such means into a proper position for igniting the torch, 20 without regard to the position of the torch in use; the body of the torch being adapted to be filled with a fuel soaked filling through which air is directed under pressure, to provide the fuel vapor for the torch.

25 In the drawings:—

Figure 1 is a perspective view of the improved torch.

Fig. 2 is a longitudinal sectional view, partly in elevation, of the same.

30 Figs. 3 and 4 are broken views in elevation illustrating the adjustability of the igniting means.

In the form of torch illustrated in Figs. 1 and 2, the torch comprises a cylindrical body 35 1 having removable ends 2 and 3, whereby the body may be substantially filled with a material such as waste 3' previously soaked in gasolene or the like. A nipple 5 projects from one end as 3 to receive a coupling 6 to 40 which is attached a flexible hose 7, which may have a mouth piece 8 to permit the operator to blow air through the body 1, or such hose may be adapted for connection to any suitable source of air under pressure.

45 The end 2 of the body is provided with a nipple 9, which through a union 10, supports a hollow and rigid conduit 11, terminating in a torch jet end 12, of any appropriate type.

50 An igniting means is supported upon the conduit 11, and as shown comprises a body 13 to receive alcohol or the like, a wick 14 extending through a wick-tube 15 projecting from the body, and adjustable through the

usual means 16, providing for burning the 55 alcohol at a point beyond the body as is desired. One end of the body 13 has a connector 17, adapted to slidably engage the conduit 11, a second connector in the form of clamping jaws 18 projecting from the body 13 and being adapted to embrace the conduit 11. The jaws 18 are designed to be clamped onto the conduit 11 to secure the igniting means in fixed relation to the conduit through the medium of a clamping 60 screw 19.

It is to be particularly noted that the igniting means or lamp is adjustable lengthwise the conduit 11, or conduit 23 of the modified form in order that in whatever position the torch may be used, the flame from the lamp, indicated at 27, in Figs. 3 and 4, will reach the end of the jet nozzle to ignite the fuel issuing therefrom. In Fig. 3, the torch is in use with the jet end elevated, in 70 which event the lamp will be moved toward the body 1, so that the flame which of course rises vertically will reach the end of the jet nozzle; while in Fig. 4 the torch is shown as being used in a position with the jet 75 nozzle extended downwardly, under which conditions the lamp will be adjusted from the body 1.

In the use of the torch, the lamp is ignited, and upon air being blown through the hose 85 pipe connection 7, either from the mouth of the user or from any suitable source of air pressure, a fuel vapor is forced from the jet nozzle of the torch and immediately ignited. The usual time employed in heating a generator 90 on the torch to generate gas is entirely obviated with the present construction, and by controlling the air pressure, the length of the flame from the torch may be similarly controlled.

95 What I claim is:—

A blow torch comprising a container containing absorbent material impregnated with liquid fuel, a tube communicating with one end of the container to supply air under 100 pressure through the absorbent material, a rigid tubular nipple extending from the opposite end of the container, a coupling connected to the nipple, a stiff tubular element extending from and connected to the flexible coupling, a burner at the end of the stiff tubular member, a liquid container provided at one end with a burner disposed adjacent

to and spaced from the burner on the stiff tubular element, a pair of connectors on the liquid container, each connector having a bearing through which the stiff tubular member passes to form a support for said member, one of said members having a screw and coöperating nut whereby to removably

clamp the connector to the tubular member to provide for the adjustment of the liquid container lengthwise said member and in 10 parallelism therewith to thereby set the burners in relative adjusted positions.

In testimony whereof I affix my signature.

JAMES A. ANDERSON.
